UNITED STATES PATENT OFFICE.

ROSCOE C. ROBERTS, OF PEN ARGYL, PENNSYLVANIA.

ABRADING-MACHINE.

1,247,152.

Specification of Letters Patent. Patented Nov. 20, 1917.

Application filed February 12, 1917. Serial No. 148,168.

To all whom it may concern:

Be it known that I, ROSCOE C. ROBERTS, a citizen of the United States, residing at Pen Argyl, in the county of Northampton and 5 State of Pennsylvania, have invented certain new and useful Improvements in Abrading-Machines; and I do declare the following to be a full, clear, and exact description of the invention such as will enable others skilled in the art to which it 10 appertains to make and use the same.

My invention has for its object to provide a comparatively simple and inexpensive yet an efficient machine for abrading purposes, 15 such as finishing slate blackboards, slabs and the like.

With the foregoing general object in view, the invention resides in the novel features of construction and unique combinations of 20 parts to be hereinafter fully described and claimed, the descriptive matter being supplemented by the accompanying drawings which constitute a part of this application and in which,

25 Figure 1 is a side elevation of the improved machine;

Fig. 2 is a top plan view thereof;

Fig. 3 is an end elevation partly in section;

30 Fig. 4 is an enlarged vertical section through one of the abrading tools showing more particularly the attachment thereof to its operating shaft; and

Fig. 5 is a detail vertical section on the 35 plane of the line 5—5 of Fig. 4.

In the drawings above briefly described, the numerals 1 have reference to a pair of suitably shaped parallel tracks extending horizontally and connected at their ends by 40 transverse bars 2 having supporting legs 3. A work supporting carriage 4 is slidably mounted on the tracks 1 and preferably includes a cast metal frame and wooden slats 5 secured thereto.

45 The carriage 4 carries a central nut 6 of any suitable formation which receives therein a longitudinal feed screw 7, said screw having on one end a beveled gear 8 meshing with a pinion 9 on a transverse shaft 10, the 50 outer end of said shaft being equipped with a pair of loose pulleys 11 and a fixed pulley 12 interposed between them, these pulleys co-operating with a pair of belts 13 and 14, one of which is crossed, a suitable belt 55 shifter 15 being provided for moving either

one of said belts onto the fixed pulley 12 and simultaneously shifting the other belt onto one of the loose pulleys 11. Both belts 13 and 14 pass around a pulley 16 on the main drive shaft 17 of the machine, which 60 shaft is in turn driven by a pulley 18 around which the belt travels. By this arrangement of parts it will be obvious that the screws 7 may be rotated in either direction for moving the carriage 7 along the tracks 65 1 as required.

The drive shaft 17 extends transversely of the machine and is rotatably mounted in bearings 19 carried by the upper ends of a pair of vertical standards 20 which rise 70 rigidly from the tracks 1, being secured thereto in any preferred manner midway the ends thereof. Extending between the standards 20 is an upper bar 21 and a lower bar 22 both of which are disposed horizontally and carry bearings 23 in which a plurality of vertical shafts 24 are rotatably and slidably mounted, the upper ends of all of said shafts being provided with intermeshing spur gears 25 through which they slide. 80 The central gear 25 is provided with a beveled gear 26 meshing with a similar gear 27 on the drive shaft 17 so that all the shafts 24 will be driven at a uniform speed and the movement thereof will be synchronized. 85

Between their ends the shafts 24 are provided with collars 28 which rest rotatably on a horizontal transverse lift bar 29 through which all of said shafts pass, the 90 ends of said bar being received in vertical slots 30 formed in the standards 20. One end of bar 29 has a nut 31 in which a vertical screw 32 is threaded, said screw being rotatably mounted in suitable bearings 33 95 carried by one of the standards 20 and having on its upper end a hand wheel or the like 34 by means of which it may be rotated. A link 35 depends from the bar 29 adjacent the nut 31 and at its lower end is mounted 100 on a crank 36 on one end of a transverse shaft 37 which extends beneath the tracks 1, the other end of said shaft having another crank 38 from which a link 39 rises, the upper end of said last named link being 105 connected to the end of the bar 29 remote from the nut 31. By this arrangement of parts rotation of the screw 32 in the proper direction will exert an equal upward thrust on both ends of the bar 29, this movement 110

serving to raise all of the shafts 24 to elevate the abrading tools 40 above the work. Rotation of the screw 32 in the opposite direction will permit said tools to lower by 5 gravity to perform their functions when the machine is set in operation, and as the tools in question operate upon the slate or the like, the dust will preferably be carried off through a suitable hood 41.

10 Each tool 40 includes a rectangular block 42 of suitable composition, the upper end of said block being cemented in a socket 43 in the lower side of a comparatively flat head 44, said head having a pair of opposed 15 side flanges 45 between which a pivot bolt 46 passes. The head 44, directly beneath the bolt 46, is formed with a channel 47 which, in transverse section, is formed on an arc described around a center located a considerable 20 distance above said bolt. This channel receives loosely therein an elongated rocker 48 which, in transverse section, is formed on an arc of less radius than that of the groove 47, so that the edges of said 25 rocker will be spaced from the wall of channel 47, as shown clearly in Fig. 5. This permits the block 42 to have a limited amount of rocking movement so that it may pass freely over irregularities in the slab or the like upon which it is operating.

30 Each of the rockers 48 has formed integrally with its upper side an eye or guide 49 equipped with a set screw 50, the several eyes of the numerous tools 40 being mounted adjustably on arms 51 which project rigidly from the lower ends of the shafts 24 at right angles thereto, movement of said eyes, after once adjusted, being prevented by the set screws 50.

40 The arrangement of parts just described mounts the tools 40 eccentrically on the shafts 24 and said tools are of such size as to cause each of the same to overlap the area operated on by the adjacent tool. The 45 entire upper surface of the work will thus be effectively finished as the several tools are operated while feeding the carriage 5 along the tracks 1.

Although the operation of the machine 50 will probably be understood from the foregoing, it may be briefly explained as follows: The work is laid upon the carriage 4 and if necessary clamped in place by any suitable means, the tools 40 being then elevated. They are now lowered by means of the screw 34 and the shaft 17 is set in motion. This drives the shafts 24 which in turn move the tools 40 over the work, the path of each tool overlapping the path of 55 its companion tools. In the meantime the carriage 4 is fed along the tracks 1 by the screw 7 and when required may be reversed by proper manipulation of the belt shifter 15.

On account of the simplicity, ease of oper-

ation and efficiency of the construction 65 shown and described, it constitutes the preferred form of the machine, but it is to be understood that within the scope of the invention as claimed, numerous minor changes 70 may be made without sacrificing the principal advantages.

I claim:—

1. An abrading machine comprising a pair of spaced parallel horizontal tracks, a flat carriage movable along said tracks for supporting the work, a pair of rigid standards rising from said tracks, upper and lower rigid horizontal bars extending between and supported by said standards, each bar having a plurality of bearings, a plurality of vertical shafts rotatably mounted in said bearings, intermeshing spur gears of uniform size slidably keyed on the upper ends of said shafts and resting on the uppermost bar, a beveled gear for one of said spur 35 gears, a second beveled gear meshing with said first named gear, a horizontal drive shaft upon which said second beveled gear is carried, bearings for said shaft carried by the upper ends of said standards, the intermediate portions of the latter having vertical slots, a third horizontal bar arranged between the aforesaid bars and having its ends received in said slots, collars on said vertical shafts resting on said third bar, a nut 95 carried by one end of this bar, a screw rotatably mounted on one of the standards and threaded through said nut, a shaft extending below the aforesaid tracks and having cranks on its opposite ends extending in the 100 same direction, and links rising from said cranks and connected to the opposite ends of said third bar.

2. An abrading machine comprising a horizontal work support, a frame rising 105 therefrom, a plurality of vertical shafts rotatably and slidably mounted in said frame, the lower ends of said shafts having abrading tools, means for driving said shafts, a horizontal bar through which said shafts 110 pass rotatably, the ends of said bar extending through vertical slots in the side of the frame, collars on the shafts resting on said bar, means for adjusting one end of said bar vertically, a link depending from said 115 end, a transverse rock shaft adjacent the work support and having a crank arm to which said link is connected, another crank arm on said rock shaft extending in the same direction as the first named arm, and an additional link rising from said second crank arm and connected to the end of said bar remote from said raising means.

3. An abrading machine comprising a driven shaft, a rigid arm extending laterally from one end thereof, a rocker carried by said arm and having its lower side curved on a comparatively short radius, an abrad-

ing tool beneath said rocker having a groove receiving the same, the bottom of said groove being curved on a larger radius than said lower side of the rocker, and a pivot 5 connecting the rocker and tool and passing through the former below the center around which its curved lower side is described.

In testimony whereof I have hereunto set my hand in the presence of two subscribing witnesses.
